4 Claims. (Cl. 175—53)

This invention relates to roller-type enlarging or reaming bits having a plurality of freely rotatable cutting rollers mounted on arms distributed in the form of a star on a base body, as used in so-called pulling or drawing drilling for enlarging or reaming out preparatory drill-holes through which the drilling rod is then passed.

In the known types of such tools the cutting rollers, which sweep over the annular shoulder between the periphery of the enlarged drillhole and the preparatory drillhole during the rotation of the drilling rod, are equipped with a plurality of cutting ribs or serrations distributed in the axial direction over their periphery. These cutting ribs are forced into the solid rock under the pulling action exerted on the drilling rod and break away the rock to be broken down peripherally of the drillhole. In view of the only linear contact between the cutting ribs and the base of the drillhole the cutting ribs, which follow very closely one to the other, are subjected to extremely heavy mechanical stresses and wear out very rapidly even if, accepting the correspondingly higher cost, they are made of specially wear-resistant material.

Furthermore, the pulling forces which can be exerted by the drilling rod on tools equipped with such cutting rollers are limited. On a given maximum pulling force being exceeded, this pulling force depending in any individual case on the hardness of the rock, the cutting rollers tend to jam temporarily and then to continue to turn spasmodically through a larger peripheral distance, which results in correspondingly intermittent stresses on the drilling rod.

The present invention provides a roller-type enlarging bit which obviates these drawbacks and is achieved by a structure which typically comprises a drill stem to be pulled through a pilot hole, at least two pins radially extending from the trailing end of the drill stem, the axis of each of the pins being inclined toward the direction of travel, and a cutter rotatably mounted on each of the pins, each of the cutters being provided with a plurality of spaced circumferential rows of wedge-shaped cutting ribs.

By this arrangement of the cutting ribs, the cutting rollers, under the influence of the pulling force exerted by the drilling stem, effectively break away the rock adjacent the ribs toward the axis of the pilot hole during the circular paths ascribed by the rollers.

The pressure component acting in the direction of the preparatory drillhole is obtained by wedge-shaped profiling of the cutting ribs in such manner that the inclination of the wedge-shape to a plane normal to the axis of the cutting roller is greater on the side directed towards the preparatory drillhole than on the side facing away therefrom.

The action of the cutting rollers constructed in the manner set forth in its essentials above is also assisted in that the cutting ribs of the successive rollers arranged at equiangular separation around the periphery of the drilling rod, for instance the cutting ribs of three such rollers, are offset with respect to one another, so that the succeeding roller in each case becomes operative in the area between the grooves formed by the cutting ribs of the preceding roller.

2

By designing the cutting rollers according to the invention, completely smooth running of the cutting rollers is obtained and the danger of any jamming of the rollers is eliminated. Due to these facts it becomes possible to operate with greater pulling forces on the drilling rod and thus to achieve a higher rate of advance in the drilling operation, intermittent stressing of the drilling rod being entirely obviated.

The invention also includes a cutting roller for a roller-type enlarging bit, said cutting roller according to the invention having cutting ribs arranged so that they extend coaxially to one another in the peripheral direction of the roller and at axial intervals from one another.

The details and further features of the invention will appear from the following description of an embodiment of the new roller-type enlarging bit given with reference to the accompanying drawings, which are merely diagrammatic.

20 In the drawings:

FIGURE 1 illustrates in side elevation the general arrangement of the tool inserted in a drillhole which is to be enlarged with parts removed to more clearly illustrate the structure,

25 FIGURE 2 is a plan view of the general arrangement illustrated in FIG. 1 showing the bit in its operative position, as in FIG. 1, inserted in a drill hole bottom of the drillhole,

30 FIGURE 3 is an enlarged fragmentary elevational view of the cutter illustrated in FIGS. 1 and 2, and

FIGURE 4 is a plan view of a tool similar to that illustrated in FIGURE 2 and specifically illustrating a modified form of the arrangement of the cutting ribs on the associated cutters.

35 In FIGURE 1, the reference letter *a* designates the drilling rod of the new drilling tool, which carries the base body *b* of three-armed type according to the embodiment, on the arms *c* of which, that is the terminal spigots thereof, the cutting rollers *d* are exchangeably mounted in the usual manner.

In FIGURE 2 there can be seen the effect of the offsetting with respect to one another of the series of cutting ribs of the several cutting rollers following one another in the peripheral direction.

45 The unique design of the rollers which forms the subject-matter of the invention is apparent in particular from FIGURE 3. In this figure there can be seen the cutting ribs *e*—there are five such ribs according to the embodiment—arranged in the direction of the periphery of the roller body at suitable axial intervals from one another.

As shown at *f*, the effective edges of these cutting ribs are so profiled in tilted gable-roof or wedge-like fashion that the inclination of the side *f'* of the wedge-shape facing the preparatory drillhole with respect to a plane normal to the axis of the roller is greater than that of the side *f''* remote from the drillhole, which latter side of the gable roof, according to the embodiment, extends parallel to the axis of the drillhole. Of course, the cutting ribs are toothed, as indicated in purely diagrammatic

55 manner in FIGURE 3 by showing a few teeth. It will be appreciated that the cutting ribs *e* have a wedge-like asymmetrical profile such that the inclination of the faces *f'* of the ribs *e* which face toward the body portion of the drill stem with respect to a plane normal to the axis of the roller *d* is greater than the inclination of the face *f''* directed toward the circumference of the bore hole.

60 In FIGURE 3, arrows *g'*, *g''* indicate the resulting force components, namely the breaking-up component *g'* acting in the direction of the axis of the drillhole and

the forcing-away component g'' acting towards the preparatory drillhole.

The circumferences of the cutting ribs, which increase in the direction of the periphery of the enlarged drillhole, are determined by the conventional inclined position of the annular bottom of the drillhole.

In addition to the advantages as regards function already described above, the roller-type bit according to the invention also has the further advantage that manufacture, including the application of the wear-resistant hard surfacing h indicated in FIGURE 3, is simpler and accordingly cheaper.

FIGURE 4 illustrates a modified form of the invention wherein the cutting ribs on one of the cutting rollers is offset in an axial direction with respect to the cutting ribs of the succeeding cutting roller. More specifically, the cutting roller d' is provided with cutting ribs e' which are offset with respect to the cutting ribs e on the cutting roller d ; while the cutting ribs e'' on the cutting roller d'' are offset with respect to the cutting ribs e' on the cutting roller d' .

The conventional practice utilized in the assembly and use of roller-type enlarging or reaming bits is described in detail in the German mining journal entitled "Glückauf," April 23, 1955, page 446.

Of course, the invention is not limited to the form of embodiment described above in detail and illustrated in the drawings, numerous modifications being possible in relation thereto without departing from the basic idea of the invention as defined by the claims.

We claim:

1. A roller-type enlarging bit comprising a drill stem having a longitudinal axis, a body portion mounted on one end of said drill stem, the other end of said drill stem adapted to extend in a pilot drill hole, pin members extending from said body portion in a star-like fashion,

the axes of said pin members being inclined relatively to the longitudinal axis of said drill stem, and a cutting roller mounted to rotate about an axis on each of said pin members, each of said cutting rollers having a plurality of circumferentially disposed cutting ribs of wedge-shaped cross sectional profile, the inclination of the portion of the wedge-shaped cross section of said cutting ribs with respect to a plane normal to the axis of said cutting roller being greater on the side of said cutting rib facing towards said body portion than on the side facing away therefrom.

5 2. A roller type enlarging bit as claimed in claim 1 wherein the cutting ribs of the one of said cutters is offset with respect to the cutting ribs of the succeeding one 10 15 of said cutters.

3. A roller type enlarging bit as claimed in claim 2 wherein the wedge-shaped cross-section of said cutting ribs is unsymmetrical.

4. A roller type enlarging bit comprising a drill stem 20 to be pulled through a pilot hole, said drill stem having a longitudinal axis, at least two pins radially extending from the trailing end of said drill stem, the axis of each of said pins being inclined away from the direction of longitudinal travel of said drill stem, and a cutter rotatably 25 mounted on each of said pins, each of said cutters being provided with a plurality of spaced circumferential rows of wedge-shaped cutting ribs, said drill stem providing the sole means for transmitting rotary motion to said pins and rotably mounted cutters and for maintaining 30 pressure on said cutters in the direction of cutting.
